UNITED STATES PATENT OFFICE.

DAVID L. LINDQUIST, OF YONKERS, NEW YORK, ASSIGNOR TO OTIS ELEVATOR COMPANY, OF NEW YORK, N. Y., A CORPORATION OF NEW JERSEY.

ALTERNATING-CURRENT ELECTROMAGNET.

1,186,011.

Specification of Letters Patent.

Patented June 6, 1916.

Application filed February 6, 1913, Serial No. 746,445. Renewed November 9, 1915. Serial No. 60,530.

To all whom it may concern:

Be it known that I, DAVID L. LINDQUIST, a subject of the King of Sweden, residing at Yonkers, in the county of Westchester 5 and State of New York, have invented a certain new and useful Improvement in Alternating-Current Electromagnets, of which the following is a specification.

The invention relates to an alternating 10 current electro-magnet, of the general type disclosed in U. S. Letters Patent No. 744,773, granted to me November 24, 1903, and more particularly to the specific type disclosed in U. S. Letters Patent No. 1,005,855, granted 15 to me October 17th, 1911, wherein the core carries secondary conductors, in which is induced a current different in phase from that energizing the primary coil. As set forth in the aforesaid Letters Patent, such 20 an alternating current magnet will hold its moving core member firmly in attracted position without vibration or chattering.

My present invention consists in the secondary conductor, or conductors, made in 25 the form of a straight bar or rod disposed transversely across and preferably through the laminated core. The secondary current then circulates within the mass of said bar, as hereinafter explained.

30 In the accompanying drawings—Figure 1 is a longitudinal section of an alternating current electro-magnet embodying my present invention. Figs. 2 and 3 are similar views of modified forms thereof. Fig. 4 is 35 a vertical section on the line x, x of Fig. 1. Fig. 5 is a similar section on the line y, y of Fig. 3. Fig. 6 shows diagrammatically the current path in bar F, viewed in plan.

Similar letters of reference indicate like 40 parts.

A is the primary coil, inclosed in a casing B. The laminated core is formed in two parts C and D. The part C is clamped in the casing by the set screw E, and the 45 part D is movable in the coil, and constitutes the armature.

In the form shown in Fig. 1, a straight bar or cylinder F of magnetic material is secured transversely across the core laminations, and preferably passes through them. Said bar may serve as a rivet to hold the laminations together.

When single-phase alternating current is supplied to the coil A, a current of different 55 phase is induced in the bar F, and circulates

therein, as shown in Fig. 6, in a direction at right angles to the core laminations, this mode of excitation being the well known split-phase inductive method. As already fully explained in my previous patents, under these conditions the current energizing the magnet never falls to zero, and by reason of the magnetic symmetry, a constant resultant pull in a straight line coincident with the axis of symmetry of the 60 magnet is exerted upon the armature D to hold it firmly attracted, without chattering or vibration.

The bar F may be a part of the stationary 65 portion C of the core, or of the movable portion D, or of each portion C and D, as shown in Fig. 2. Instead of using but one bar F, as shown in Fig. 1, I may employ a plurality of bars F, G, as shown in Fig. 3. Where one of said bars, as G, is placed 70 farther away from the pole than the other bar, F, it will produce a less magnetic effect.

With this construction, I can do away 75 with secondary coils and pole-pieces, substituting the simple straight bar, and utilizing it mechanically, if desired, as a rivet.

I claim:

1. An alternating current electro-magnet of the type set forth, comprising a primary coil, a laminated core, and a conductor furnishing a closed secondary circuit in the form of a straight bar of magnetic material extending transversely across the laminations of said core and having its end pieces terminating in proximity to opposite surfaces thereof.

2. An alternating current electro-magnet of the type set forth, comprising a primary coil, a laminated core, and a conductor furnishing a closed secondary circuit in the form of a bar of magnetic material extending transversely across and through the laminations of said core.

3. An alternating current electro-magnet of the type set forth, comprising a primary coil, a laminated core, and a plurality of conductors each furnishing a closed secondary circuit in the form of separate bars of magnetic material extending transversely across the laminations of said core.

4. An alternating current electro-magnet of the type set forth, comprising a primary coil, a laminated core, and a plurality of conductors each furnishing a closed secondary circuit in the form of separate bars of

magnetic material extending transversely across the laminations of said core and disposed at different distances from a polar extremity thereof.

- 5 5. An alternating current electro-magnet of the type set forth, comprising a primary coil, a laminated core, and a rivet of magnetic material extending transversely across

and through the laminations thereof and forming a secondary to said primary coil. ¹⁰

In testimony whereof I have affixed my signature in presence of two witnesses.

DAVID L. LINDQUIST.
